UNITED STATES PATENT OFFICE.

THEODOR JESSEN, OF ALTONA-BAHRENFELD, GERMANY, ASSIGNOR TO THE FIRM OF BLOHM & VOSS, KOMMANDIT-GESELLSCHAFT AUF AKTIEN, OF HAMBURG, GERMANY.

ELECTRIC CHANGE-OVER SWITCH.

1,152,516.

Specification of Letters Patent. Patented Sept. 7, 1915.

Application filed February 24, 1914. Serial No. 820,751.

To all whom it may concern:

Be it known that I, THEODOR JESSEN, citizen of Prussia, Germany, residing at 16 Händelstrasse, Altona - Bahrenfeld, Germany, have invented certain new and useful Improvements in Electric Change-Over Switches, of which the following is a specification.

This invention relates to an improved 10 electric change-over switch for selectively connecting a feeder line connected with a current consuming device, such as a motor, series of lamps or the like, to any one of a plurality of independent supply lines or 15 current sources.

The present invention relates more particularly to change-over switches of the type in which a two-way switch is adapted to make contact with either of a pair of movable selectors adapted to establish connection with the desired supply-line or current source.

The object of the present invention is to 25 provide an instantaneous change-over switch of this type, thus preventing interruption when changing-over the current supply from one supply line to another.

A further object of the invention is to 30 simplify the construction of the switch and also enable ready supervision of the connection established.

According to the present invention the two-way switch comprises two switch levers coöperating in such a manner that, when 35 the current is changed over, the switch lever, which is in circuit through one of the selectors, is switched off shortly before the other switch lever establishes contact through the other selector with the newly 40 selected supply line or current source so that, at the instant of changing-over, the current supply lines or current sources are put in parallel with one another through the arcs formed at the moment of breaking 45 the circuit, interruptions being thereby avoided and the arcs being rapidly extinguished or ruptured during the changing-over operation.

The switch lever in the circuit is held 50 in position by current conducting springs

and is connected by a spring with the other switch lever so that, during the switching operation, the first switch lever first of all remains in closed position, while tensioning the spring connecting the switch levers, until it is positively switched off by the engagement of stops on the switch levers, both switch levers being now rapidly moved under the tension of the connecting spring while the current conducting springs temporarily continue to conduct the current. Each selector preferably comprises a contact brush, one end of which constitutes a contact face for the two-way switch, thus providing a very simple construction and insuring the least possible resistance within the switch.

In order that the invention may be more clearly understood reference is made to the accompanying drawings illustrating the 70 simplest form of the invention by way of example.

Figure 1 is a switch diagram with a two-pole switch and Fig. 2 a similar switch diagram with a one-pole switch. Fig. 3 is a 75 side view of the change-over switch partly in section. Fig. 4 is a similar view to Fig. 3 showing the position of the parts during the changing-over operation. Fig. 5 is a face view of the switch shown in Fig. 3. Fig. 6 is a detail view in section on the line 80 A-B of Fig. 5.

The contacts I, II, III, IV, V (Figs. 1 and 2) of the two selectors are in connection with the several current generators D_I, D_{II}, D_{III}, D_{IV}, D_V as illustrated. Between the two selectors is arranged the two-way switch in series circuit therewith. The movable selectors comprise brushes *a* (Figs. 3 to 6) consisting of several thin metal strips secured to the lever *b* which is rotated by a suitable handle. The brushes *a* lead the current to the two-way switch, that is to say, to the switch levers *c* which are adapted to be alternately thrown into operative position, and from thence to the bracket and feeder line terminal *d* which is connected with the current consuming device represented as a motor in Fig. 1 and as a series of lamps in Fig. 2. The two switch levers *c* 95

are connected together by means of a spring *n* and are each provided with a stop *g* on their pivoted ends. The switch lever *c* is held in its closed position by means of 5 springs *m* which also serve as arc attractors and engage over the edges of the contact plate of the switch lever *c*.

Notched segments *e* consisting of insulated material and being rotatable with the selector levers *b* secure the selectors against rotation so long as the corresponding switch lever *c* is in closed position, the segments *e* having a plurality of notches corresponding in number to the number of contacts engaged 10 by a nose *f* on the switch lever *c*. The nose *f* is of such length and arranged at such an angle to the stop *g* on the switch lever *c* that it is impossible to switch on the switch lever *c* which bears with its nose *f* against the segment *e* or to switch off the switch lever which is in closed position before the newly adjusted selector *a* is adjusted onto the middle of the contact (Fig. 5). Springs *h* (Fig. 3) at the pivotal points of the selector levers *b*, 15 press the buttons *i* into their notches and thus insure proper adjustment of the selectors *a*. Each selector may take up a position in which the brushes are disconnected from all the current sources (D_1 to D_5) to enable 20 the current to be entirely switched off. If now, for example, in Fig. 1 the motor is connected through the righthand selector to the current generator D_{IV} and it is to be connected to the current generator D_{II} the brush 25

a of the left selector which is without current, is adjusted on to the contact II , and the switch lever *c* is then changed over by means of a switch handle *k* so that, for example in Fig. 3, the upper switch lever *c* no longer bears against the upper brush *a*, but on the contrary the lower switch lever *c* will bear against the lower brush *a*.

The insulated switch handle *k* is pivoted on the same axis as the switch levers *c* and 45 during the switching operation moves one or other of the levers *c* with it by means of an abutment *l*. Since now the lever *c* which is still in closed position is held in this position by the springs *m*, the spring *n* will be tensioned on turning the other switch lever. The spring *n* will continue to be tensioned until the stops *g* collide as in Fig. 4, whereupon the closed switch lever will also be moved. As soon as the contact plate of 50 the lever which has been switched off has during this operation spread the springs *m*, it will be rapidly moved by the tension of the spring *n* and the arc formed at the moment of breaking the circuit during the disconnection will therefore be ruptured as rapidly as possible and the other switch lever, in case it has not been brought into proper closed position, will be forced into position, the brush being depressed and the springs *m*

then springing over the edges of the contact plate and holding the latter firmly in closed position. 65

When the contact plate leaves the contact surface of the brush, the springs *m* undertake the conduction of the current during 70 the movement of the contact plate between the springs and during the formation of the arc which subsequently takes place, until the voltage in the circuit during the changing is restored by the new current source switched 75 on through the other throw-over lever, thereby insuring that the contact plate leaves the sensitive brush without current. By the restoration of the voltage in the circuit at the instant of the formation of the arc the latter 80 collapses before it is ruptured by the increasing distance of the contact face from the springs *m*, thus insuring that the current supply to the feeder line will not be interrupted during the switching operation, but 85 only subjected to a voltage variation.

The arrangement of the two selectors and the two-way switch in series therewith in the manner hereinbefore described enables the connection which has been effected 90 through the instantaneous change-over switch to be easily observed from the position of the switch levers and from the position of the selectors. In the case of multipole instantaneous change-over switches, as 95 many selectors and two-way switches may be combined as there are poles.

I claim:

1. An electric-change-over switch for selectively connecting a feeder line to any one 100 of a plurality of independent supply lines comprising two sets of supply line contacts, a pair of movably mounted selectors each movable over one set of said contacts, a pair of movably mounted switch members each 105 adapted to close upon and make contact with one of said selectors, means for closing and opening said switch members, said means operating to open one of said members shortly before the other member reaches its 110 closed position, and a feeder line terminal connected to said switch members.

2. An electric change-over switch for selectively connecting a feeder line to any one of a plurality of independent supply lines 115 comprising, in combination, two sets of supply line contacts mounted on a support, two movably mounted selectors, each movable over one set of said contacts, a feeder line terminal mounted on said support between 120 said contacts, and a switch mounted between said selectors comprising two pivoted levers in electrical connection with said terminal and each adapted to close upon one of said selectors, a tactile spring connecting 125 said levers, a stop on each lever, said stops co-acting when one of said levers is in closed position and when the other is nearly

in closed position, and means for moving said levers alternately into closed position.

3. An electric change-over switch for selectively connecting a feeder line to any one of a plurality of independent supply lines comprising, in combination, a multi-series of supply line contacts, a plurality of movably mounted selectors, each movable over one series of said contacts, a pair of movably mounted switch members for each pair of selectors, feeder line terminals in electrical connection with said switch members and means for moving the switch members of each pair alternately into conducting relationship with said selectors.

4. An electric switch comprising, in combination, a switch board, a pair of supply line contacts thereon, a feeder line terminal mounted on said board, a pair of levers pivotally mounted on said board in electrical connection with said terminal and each adapted to close upon one of said contacts, a spring connecting said levers, yielding lugs holding the switch closed against the action of the spring, an abutment on each of said levers, said abutments being adapted to release the levers from the lugs and to collide when one of said levers is in closed position and when the other lever is nearly in its closed position and means for alternately closing said levers.

5. An electric switch comprising, in combination, a switch board, a pair of supply line contacts thereon, a feeder line terminal between said contacts, a pair of levers mounted on a common pivot on said board in electrical connection with said terminal and each adapted to close upon one of said contacts, a tractile spring connecting said levers, yielding lugs holding the switch closed against the action of the spring, an abutment on each of said levers, said abutments being adapted to release the levers from the lugs and to collide when one of said sleeves is in closed position and when the other lever is nearly in closed position, a pivotally mounted operating handle and an abutment on said handle adapted to alternately engage said levers.

50 6. An electric change-over switch for selectively connecting a feeder line to any one of a plurality of independent supply lines comprising, in combination, two sets of supply line contacts, two movably mounted selectors, each movable over one set of said contacts, a feeder line terminal mounted on said support between said contacts, and a switch mounted between said selectors comprising two pivoted levers in electrical connection with said terminal and each adapted to close upon one of said selectors, a tractile spring connecting said levers, yielding lugs holding the switch closed against the action of the spring, a stop on each lever, said stops

releasing the levers from the lugs and co-acting when one of said levers is in closed position and when the other is nearly in closed position, means for moving said levers alternately into closed position and flexible current conducting elements on said 70 selectors adapted to engage said switch members when the latter are in or near their closed position.

7. An electric change-over switch for selectively connecting a feeder line to any one of a plurality of independent supply lines comprising, in combination, two sets of supply line contacts, two movably mounted selector members each movable over one set of said contacts, a metallic brush mounted in each of said selector members and projecting therefrom, a pair of movably mounted switch members each adapted to be put in conducting relationship with one of said brushes, means for alternately putting said 85 switch members into conducting relationship with said brushes and a feeder line terminal connected to said switch members.

8. An electric change-over switch for selectively connecting a feeder line to any one of a plurality of independent supply lines comprising, in combination, two sets of supply line contacts, a metallic brush for each set of contacts, a rotatable handle in which each brush is mounted so as to project at 90 each end therefrom, said handle being adapted to move the brush over its own set of contacts, a feeder line terminal between said contacts, a support connected to said terminal, a pair of switch levers pivotally 100 mounted on a common axis on said support, each of said levers being adapted to contact with one end of one of said brushes, a switch handle adapted to alternately rock said levers, a tractile spring between said levers, 105 yielding lugs holding the switch closed against the action of the spring, an abutment on the pivotal end of each of said levers, said abutments releasing the levers from the lugs and co-acting when one of 110 said levers is rocked, and a pair of current-conducting spring elements mounted on each of said handles, one on each side thereof.

9. An electric change-over switch for selectively connecting a feeder line to any one of a plurality of independent supply lines comprising, in combination, two sets of supply line contacts, a metallic brush for each set of contacts, a rotatable handle in which each brush is mounted so as to project at 115 each end therefrom, said handle being adapted to move the brush over its own set of contacts, a feeder line terminal between said contacts, a support connected to said terminal, a pair of switch levers pivotally 120 mounted on a common axis on said support, each of said levers being adapted to contact with one end of one of said brushes, a switch

handle adapted to alternately rock said levers, a tractile spring between said levers, yielding lugs holding the switch closed against the action of the spring, an abutment on the pivotal end of each of said levers, said abutments releasing the levers from the lugs and co-acting when one of said levers is rocked, a pair of current-conducting spring elements mounted on each 10 of said handles, one on each side thereof, a

notched segment on each of said handles and a projection on each of said levers adapted to engage the corresponding segment.

In testimony whereof I have affixed my 15 signature in presence of two witnesses.

THEODOR JESSEN.
